CLAIM

The ornamental design for a furniture leg protector, as shown and described.

DESCRIPTION

FIG. 1 is a front and top perspective view of a furniture leg protector, showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view thereof, showing the furniture leg protector in a folded position;

FIG. 10 is a bottom plan view thereof, showing the furniture leg protector in a folded position;

FIG. 11 is a perspective cross-sectional view taken along the line 11-11 in FIG. 10; and,

FIG. 12 is a front cross-sectional view taken along the line 12-12 in FIG. 10.

The broken lines in the figures illustrate portions of the furniture leg protector that form no part of the claimed design.

1 Claim, 12 Drawing Sheets
